DRAFT REGULATOR

Herman C. Frentzel, Jr., Milwaukee, Wis., assignor to The Heil Co., Milwaukee, Wis., a corporation of Wisconsin

Application November 9, 1935, Serial No. 48,960

4 Claims. (Cl. 236—45)

The present invention relates generally to improvements in the art of heating, and relates more specifically to improvements in the construction and operation of draft regulators for controlling the quantity of combustion air admitted to the fuel chambers of furnaces, boilers or the like.

A general object of the present invention is the provision of an improved draft regulator which is extremely simple in construction, and which is moreover automatic, reliable and highly efficient in operation.

It is a well established fact that the efficiency of a heating plant is materially affected by undesirable variations in the quantity of air delivered to the fuel combustion chamber, as a result of draft variations. Automatic and accurate draft regulation is therefore desirable in order to maintain most efficient combustion and to avoid excessive heat losses through the stack, and numerous types of automatically functioning draft actuated control devices associated either with the smoke pipe or with the stack, have heretofore been proposed. With some of these prior draft regulators, more or less fresh air from the furnace room is admitted to the smoke and gas conducting conduit of the smoke pipe or stack, without actually varying the normal cross-sectional area of this conduit; while in others the conduit cross-section is varied without admitting additional air thereto. Both of these prior types possess some advantages as well as disadvantages, and under certain conditions of operation it would appear advantageous to combine these prior methods of control so as to secure the benefits of both.

It is therefore a more specific object of the present invention to provide an improved automatic damper which effectively combines the principles of operation of these two prior types of regulators, and wherein both throttling and admission of air to the smoke pipe or stack, are simultaneously effected.

Another specific object of this invention is the provision of a compact and durable draft regulating appliance for combustion chambers, which is reliable in operation, and which automatically varies the area of the gas outlet so as to maintain the supply of air admitted to the chamber, at the most efficient value.

A further specific object of the invention is to provide a new and useful damper assemblage which may be applied as a unit to various types of furnaces and boilers, and which is capable of

convenient and sensitive adjustment so as to secure any desired operation.

Still another specific object of the invention is the provision of an improved draft regulator especially applicable to oil fired combustion chambers, which is exceptionally reliable in operation and which can be manufactured and installed at moderate cost.

An additional specific object of the present invention is to provide a damper associable directly with the gas discharge end of a fuel combustion chamber, and which functions to simultaneously vary the cross-sectional area of the combustion gas discharge conduit, and to introduce inversely proportional variable quantities of ambient air to the smoke pipe beyond the combustion gas discharge opening.

These and other objects and advantages of the present improvement will be apparent from the following detailed description.

A clear conception of several embodiments of the invention, and of the mode of constructing and of utilizing draft regulating appliances built in accordance with the improvement, may be had by referring to the drawings accompanying and forming a part of this specification wherein like reference characters designate the same or similar parts in the several views.

Fig. 1 is a fragmentary part sectional side elevation of a heating plant comprising a fire-tube boiler, smoke pipe and stack, showing one of the improved regulators associated with the boiler and smoke pipe;

Fig. 2 is a fragmentary rear view of the boiler of Fig. 1, looking toward the draft regulator;

Fig. 3 is an enlarged internal front view of the draft regulator shown in Figs. 1 and 2;

Fig. 4 is a further enlarged vertical section through the draft regulating unit, taken along the line 4—4 of Fig. 3;

Fig. 5 is a similarly enlarged fragmentary internal front view of a lower corner of the unit of Figs. 3 and 4; and

Fig. 6 is a vertical section similar to that of Fig. 4, through a modified type of the improved draft regulating unit.

While the invention has been illustrated herein as being specifically embodied in a heating plant having a boiler of the fire-tube type, it is not intended to unnecessarily restrict the scope by such embodiment, since the improvement is obviously more generally applicable to other types of furnaces and combustion chambers.

Referring to the drawings, the heating system shown in Figs. 1 and 2, comprises in general a

boiler 8 having a water chamber 9 and a combustion chamber 10, the latter of which communicates with a rear gas discharge space 11 through fire-tubes 12 penetrating the water chamber 9; a chimney or smoke stack 13 ordinarily spaced some distance from the rear of the boiler 8; and a smoke pipe 14 connecting the flue of the stack 13 with the boiler space 11 through a gas discharge orifice 15 formed in a smoke box 10 or fitting 16 secured to the rear of the boiler. All of these elements are of well known construction and are subject to considerable variation in form and location, and the combustion chamber 10 may be fired with any suitable fuel such as coal, coke, oil or gas, being provided with the usual controllable means for injecting or admitting combustion air to the ignition or burning zone.

The fitting 16 which is secured to the rear of the boiler 8 and which provides a closure for the gas space 11, has a rearwardly extending continuous rectangular flange 17. The improved draft regulator constituting the present improvement, is detachably cooperable with the flange 17, and comprises generally a closure and supporting member 18 having a rear lower opening 19 and integral laterally spaced forwardly projecting parallel side walls 20 extending into the space 11; and a flat plate-like damper 21 mounted 30 to swing between the walls 20 upon aligned end pivots 22 carried by the damper 21 and coacting with bearings 23 secured to the closure member 18, see Figs. 2, 4 and 5. The member 18 has a peripheral recess 24 which is cooperable with the rear edge of the flange 17, and is swingably suspended from the fitting 16 by hinges 25, being normally held in closed position by a latch 26 as shown in Fig. 2. A curved wall 27 formed integral with the member 18, extends upwardly 40 from the lower edge of the opening 19 to the lower portions of the front edges of the side walls 20, thereby compelling all air which enters the opening 19 to pass upwardly and forwardly between these walls.

The plate damper 21 may be formed of relatively thin sheet metal, and the aligned suspension pivots 22 for this damper are carried by blocks 28 secured to the medial portions of the opposite ends of the damper, the common axis of the pivots 22 being disposed forwardly of the plane of the damper. The upper portion of the damper 21 is automatically swingable about the pivots 22 between the parallel side walls 20, from closed position as shown in solid lines in Figs. 1 and 4, 50 to open position as shown in dot-and-dash lines, by the differences in pressure acting upon the upper portion of the damper plate and caused by variations in draft conditions. When completely closed, the upper portion of the damper 21 coacts 55 with a sealing strip 29 secured to the supporting member 18; and when wide open, the damper plate coacts with the front end of the curved wall 27. The swingable damper 21 is also provided with a central stud 30 secured thereto between the blocks 28 by clamping nuts 31, and extending rearwardly toward the opening 19; and a weight 32 has screw-thread coaction with this stud 30 being adjustable therewith and adapted to be fixed in any desired position of adjustment by a lock nut 33. Because of the fact that the damper plate is disposed rearwardly of its horizontal pivotal axis and that the fixed stud 30 also extends rearwardly with respect to this axis, the off-set center-of gravity of these parts would normally 70 tend to swing the damper 21 toward the sealing

strip 29 and into closed position. In order to obviate this tendency and to balance the damper 21 upon its pivots 22, the lower depending portion 34 thereof is provided with a fixed elongated counter-balancing weight 35 having its center of gravity located forwardly of the pivotal axis, the weight 35 being of such heft that static balancing of the pivotally suspended elements, other than the adjustable weight 32 and nut 33, results. With this assemblage of elements, it will be apparent that when the adjustable weight 32 is located as near to the damper 21 as possible, the latter will be easily shifted by slight variations in pressure acting on opposite sides of the upper portion thereof, whereas adjustment of the weight 32 away from the plane of the damper will require increased pressure acting upon the rear surface of the same in order to swing it away from the sealing strip 29.

During normal operation of the improved draft regulator of Figs. 1 to 5 inclusive, and when fuel is being consumed in the combustion chamber 10 of the boiler 8, hot gases of combustion are being delivered from the fire-tubes 12 through the space 11, orifice 15 and smoke pipe 14, to the stack 13. Depending upon the setting of the mechanism for supplying combustion air, a predetermined quantity or volume of gases of combustion will normally flow through these passages to the stack 13, but any variations in draft conditions will tend to undesirably increase or decrease the quantity of combustion air and will thus tend to reduce the efficiency either by causing incomplete combustion or by overheating the liquid. The improved draft regulator may be conveniently and accurately set by adjusting the weight 32 through the opening 19, so as to automatically produce any desired condition of operation. When the weight 32 has been properly adjusted to correspond with a predetermined setting of the fuel and fresh air supply, the damper 21 will automatically adjust itself by swinging upon its supporting pivots 22, so as to simultaneously throttle the area of the passage between the space 11 and orifice 15, and to admit sufficient ambient air through the opening 19 directly to the smoke pipe 14 through the orifice 15, to meet the changing draft conditions within the stack 13, without undesirably affecting the quantity of combustion air admitted to the chamber 10. If the stack draft increases, the throttling effect upon the flow of gases of combustion will be increased and more air will be admitted through the opening 19, and vice versa; but the communication between the space 11 and orifice 15 can never be entirely interrupted. When the boiler is not in use, the damper 21 will automatically close by engaging the sealing strip 29, and the weight 32 may obviously be quickly and conveniently adjusted to secure any desired condition of draft regulation.

The modified draft regulator of Fig. 6 is quite similar in general construction, to the device of Fig. 4, but is somewhat different in principle of operation. In the modified assemblage, the plate damper 21' is provided with an arcuate sealing flange 36 at the upper swinging end thereof, and the supporting member 18' has a rear bulge 37 above the opening 19 for accommodating the swinging motion of the flange 36. The counter-balancing weight 35' is slightly enlarged to compensate for the addition of the flange 36, and this flange is adapted to maintain substantially constant sealing cooperation with a lip 38 formed upon the member 18' while the sides of the

damper 21' have like cooperation with the parallel side walls 20' for all positions of adjustment of the damper plate. The modified damper 21' is adapted when closed, to seat against sealing strips 29' carried by the member 18', but should be freely swingable without excessive friction, upon its pivots 22, as in the case of the damper 21.

During normal operation of the modified draft regulator of Fig. 6, the damper 21' will again swing back and forth about its pivots 22, as the draft in the heating system varies, but this damper will exercise only a throttling effect upon the gases of combustion, and will not admit ambient air through the opening 19 to the smoke pipe or stack. The ambient air within the furnace room will merely act upon the rear surface of the damper 21' to create a pressure thereon, and as the stack draft varies, this pressure will cause the damper plate and the flange 36 to move back and forth and to thereby vary the effective area of the orifice 15 leading to the smoke stack. The adjustable weight 32 of the modified device functions precisely the same as previously described, and when the combustion of fuel ceases, the modified damper 21' will close by engaging the sealing strips 29'.

From the foregoing description it will be apparent that the present invention provides an automatic damper or draft regulator which is extremely simple, compact, and durable in construction, and which is moreover highly efficient and reliable in its operation. The draft regulator may be readily applied as a unit to any type of combustion chamber and may be conveniently adjusted to produce any desired predetermined operation. The various elements of the improved assemblage are thoroughly protected against accidental disturbance, and the counterbalanced construction of the damper combined with the screw threaded adjustment of the weight 32, provides for extremely sensitive operation of the mechanism. In large units it may be preferable to provide anti-friction bearings for the pivots 22, but this is not necessary in smaller units where non-corrosive materials may be utilized in the construction of the pivots 22 and of the bearings 23. While the combined throttling and air admitting type of draft regulator shown in Fig. 4 is thoroughly satisfactory in most heating installations, it may be undesirable to withdraw air from the furnace room in effecting the regulation, and under such conditions the draft regulator of Fig. 6 may be more desirable. The improved draft regulating units can be readily constructed without excessive machining operations, and can therefore be manufactured and sold at moderate cost. The invention has proven highly successful in actual operation, especially when applied to oil burning heating plants, and has demonstrated its ability to insure minimum waste of heat.

It should be understood that it is not desired to limit the invention to the exact details of construction and to the precise mode of operation herein shown and described, for various modi-

fications within the scope of the claims may occur to persons skilled in the art.

I claim:

1. A draft regulator for a combustion chamber, comprising, a pivotally suspended closure member for the outlet end of the combustion chamber, said member having an opening communicating with the atmosphere and integral parallel side walls extending away from said opening into the outlet end of the combustion chamber, a damper pivotally suspended from said member and swingable between said walls to control the admission of air through said opening, said damper having a balancing weight suspended therefrom within the outlet end of the combustion chamber, and an adjustable regulating weight carried by said damper within said member and between said side walls, said regulating weight being constantly accessible for adjustment through said opening. 20

2. A draft regulator for a combustion chamber, comprising, a removable closure member for the outlet end of the combustion chamber, said member having a lower opening shielded by a wall formed integral with said member and also having integral side walls extending upwardly from said shielding wall and from said opening and into the combustion chamber, a damper pivotally suspended from said member near the inner end of said shielding wall and swingable between said side walls to control the admission of air through said opening, and adjustable regulating means for said damper housed within said member and constantly accessible for adjustment through said opening. 30

3. A unitary draft regulator for a combustion chamber, comprising, a closure member for the outlet end of the combustion chamber, said member having an opening communicating with the atmosphere and integral parallel side walls extending upwardly away from said opening, a damper pivotally suspended from said member and swingable between said walls to control the admission of air through said opening, said damper having a balancing weight fixedly attached thereto within said combustion chamber, and an adjustable regulating weight carried by said damper within said member and between said side walls, said regulating weight being accessible for adjustment from the outside through said opening. 50

4. A unitary draft regulator for a combustion chamber, comprising, a closure member for the outlet end of the combustion chamber, said member having an opening shielded by a fixed wall formed integral with said member and also having integral laterally spaced side walls extending inwardly away from said opening, a damper pivotally suspended from said member near the inner end of said fixed wall and swingable between said side walls to control the admission of air through said opening, and adjustable regulating means for said damper housed within said member and being accessible for adjustment from the outside through said opening. 60
